DESIGN FOR A TERMINAL LINK FOR A WATCH BRACELET OR SIMILAR AR- TICLE

Karl C. Augenstein, Cranston, R. I., assignor to
Speidel Corporation, Providence, R. I., a cor-
poration of Rhode Island

Application February 27, 1947, Serial No. 137,198

Term of patent 14 years

(Cl. D45—4)

To all whom it may concern:

Be it known that I, Karl C. Augenstein, a citizen of the United States of America, residing at Cranston, county of Providence, and State of Rhode Island, have invented a new, original, and ornamental Design for a Terminal Link for a Watch Bracelet or Similar Article, of which the following is a specification, reference being had to the accompanying drawing, forming a part thereof.

Fig. 1 is a top plan view of a terminal link for a watch bracelet or similar article showing my new design;

Fig. 2 is a side elevational view of the link; and

Fig. 3 is a perspective view thereof on an enlarged scale.

I claim:

The ornamental design for a terminal link for a watch bracelet or similar article, substantially as shown.

KARL C. AUGENSTEIN.
